UNITED STATES PATENT OFFICE.

LORENZO JOHNSON, OF RIRIE, IDAHO.

GATE OPENING AND CLOSING MECHANISM.

1,421,088.

Specification of Letters Patent. Patented June 27, 1922.

Application filed June 16, 1921. Serial No. 478,067.

To all whom it may concern:

Be it known that I, LORENZO JOHNSON, a citizen of the United States, residing at Ririe, in the county of Jefferson and State 5 of Idaho, have invented certain new and useful Improvements in Gate Opening and Closing Mechanism, of which the following is a specification.

This invention relates to gates, and the 10 primary object of the invention is to provide an improved and novel means for opening and closing gates at points remote therefrom, whereby persons in vehicles approaching or leaving the gates, can open or close 15 the same, without the necessity of getting out of the vehicle.

Another object of the invention is the provision of a novel means for supporting the gate, to permit the same to be readily opened 20 and closed, and to permit the same to be raised and adjusted in relation to the ground or road way, so as to overcome any sagging in the gate, or to lift the same over obstructions in the roadway.

25 A further object of the invention is to provide a novel operating device for gates comprising means arranged laterally on each side of the gate, and means arranged forwardly or rearwardly of the gate, whereby 30 the gate can be conveniently used on cross roads and the like;

A still further object of the invention is 35 to provide an improved gate operating mechanism of the above character, which will be durable and efficient in use, one that will be simple and easy to manufacture, and one which can be placed upon the market at a reasonable cost.

With these and other objects in view, the 40 invention consists in the novel construction, arrangement and formation of parts as will be hereinafter more specifically described, claimed and illustrated in the accompanying drawing, forming a part of this specification, and in which drawings:

Figure 1 is a perspective view of the improved gate and operating means therefor, the gate being shown in partly opened position.

50 Figure 2 is a fragmentary detail perspective view of one of the supporting uprights for the gate.

55 Figure 3 is a fragmentary vertical section through one of the supporting posts or uprights for the gate illustrating the means for attaching the operating ropes.

Figure 4 is a similar view showing the means of associating the supporting rollers therewith.

Figure 5 is a fragmentary side elevation 60 of one of the standards for carrying the operating ropes.

Figure 6 is a fragmentary side elevation 65 of the shears utilized for supporting the supporting rod for the gate.

Referring to the drawings in detail, wherein similar reference characters designate corresponding parts throughout the several views, the letter A indicates the gate; B, the gate carrier; and C, the operating device for the gate.

The gate A can be of any preferred construction, and is adapted to slide transversely across the roadway D, which is shown branching off from a main roadway E. 70 This gate is adapted to normally close an opening in the enclosing fence F, which as shown includes end posts 10, one of which can be provided with a suitable guide 11 for the gate A.

As shown the gate A includes end posts 12 connected by panels 13, but as heretofore stated, the gate can be constructed in any preferred way. Adjacent to the end posts 12 are secured the uprights 14, or these uprights can form continuations of the posts 12, if so desired. While the uprights 14 can be of any desired construction or formation, the same have been shown solid and provided with the vertically extending aligned 80 slots 15.

The gate carrier or supporting means B comprises a pair of shears 16 and a pair of shears 17, and these shears are located on the opposite sides of the roadway. Each of the 95 shears include a pair of legs 18 which are pivotally connected adjacent to their upper ends by means of a pivot pin or bolt 19'. These pairs of shears 16 and 17 are adapted to support the rod or supporting cable 19, 100 which is adapted to extend transversely across the roadway D above the gate A and is extended through the slots 15 formed in the uprights 14. The opposite ends of the supporting rod or cable 19 inclines downwardly as at 20, and are anchored in the ground in any suitable manner. The uprights 14 are provided with a plurality of spaced transversely extending openings 21, 105 certain of which are adapted to receive suitable removable bolts 22, which support rollers 23 which are adapted to engage the sup-

110

porting rod or cable 19. It can be seen by this construction that the gate can be readily slid transversely of the roadway, and that by raising or lowering the bolts 22 in the 5 openings 21, the position of the gate in relation to the roadway can be initially adjusted. The provision of the shears 16 and 17 also forms an important part of my invention, as it can be seen that if the gate sags through 10 any cause or the path thereof becomes obstructed by stones or the like, it is merely necessary to move the lower portions of the legs 18 of the shears closer together, which will effectively raise the supporting rod or 15 cable 19. The upper ends of the uprights 14 are braced by an upper beam 24, the terminals of which are also extended in the side portion 15 of the uprights, and these terminals can be held in place by means of 20 suitable removable bolts 24, which can be inserted in any one of the openings 21. Suitable bolts 25 are also inserted in the openings 21 above the bolts 24, and these bolts 25 serve as means for permitting the 25 operating ropes to be secured to the gate, as will be hereinafter more fully described. It can be seen that there are two of the bolts 25, one at each end of the gate.

The operating means C for the gate A 30 includes a plurality of pull ropes, and these ropes are so disposed as to permit the gate A to be operated at either side of the gate, laterally thereof, or rearwardly of the gate, as clearly shown in Figure 1 of the drawings.

35 Thus it can be seen that the gate A can be operated from three different points. Standards 27 and 28 are arranged on each side of the gate laterally thereof, and a standard 29 is arranged rearwardly of the gate.

40 The standards are disposed a sufficient distance from the gate to permit the gate to be conveniently operated by persons in vehicles or on horse back. Each of the standards 27, 28, and 29 is provided with an outwardly 45 extending arm 30, which is suitably braced in order to prevent sagging thereof. The standard 27 is provided with a pair of guide pulleys 31 and 32, the standard 28 with a pair of guide pulleys 33 and 34, and the

50 standard 29 to a pair of guide pulleys 35 and 36. An intermediate standard 37 is arranged at one side of the gate opening and between the standard 27 and 28, and this standard can be secured to one of the gate 55 posts 10 or form a continuation thereof. This post is also provided with a laterally extending arm 38, to which is secured a triple block 39. The upper end of one leg 18 of the shears 16 is provided with a pair of pulleys 40 and 41, while the upper end of the opposite leg is provided with a pair of pulleys 42 and 43. In order to open and close the gate 60 from the left hand side of the road, an adjustable rope 44 is provided, which is trained 65 around the pulley 31, around the lower pul-

ley 41, around one of the pulleys of the triple block 39 carried by the intermediate standard 37, and then back and secured to the bolt 25, which is arranged at the upper end of the standard 14 at the forward end 70 thereof. It can be seen that by giving this rope 44 a downward pull, the gate will be slid rearwardly on the cable or rod 19. When it is desired to close the gate from the left hand side, the rope 45 is pulled, which 75 will be trained around the pulley 32, around the upper pulley 40, and then extended directly to the bolt 25 at the forward end of the gate. Thus it can be seen that a pull upon this rope 45 will move the gate to its 80 closed position.

In order to permit the gate to be operated from the right hand side thereof, a pair of cables 46 and 47 are provided. The cable 46 is trained around the inner pulley 33, 85 around the pulley 48 carried by one of the legs 18 of the shears 17, around pulleys of the triple block 29 and then back to the bolt 25 carried by the upright 14 at the rear end of the gate. It can be seen that when 90 a pull is exerted on the rope 46, the gate will be slid to its closed position. The rope 47 is trained around the pulley 34, around an upper pulley 49 carried by one of the legs 18 of the shears 17, and secured directly 95 to the bolt 25 of the upright 14 arranged in the rear end of the gate A. It can be seen that when a pull is exerted on the rope 47, that a direct rearward pull will be given to the gate thus pulling the same to its open 100 position.

In order to prevent opening and closing of the gate from a point rearwardly thereof, pulling ropes 50 and 51 are provided. The rope 50 is trained around the pulley 35, 105 around the lower pulley 43 carried by one of the legs of the shears 16 and extended directly to the bolt 25 carried by the upright 14 arranged in the forward end of the gate. Thus it can be seen that when the rope 50 110 is pulled, a direct forward pull will be given to the gate, which will move the same into closed position. The rope 51 is trained around the pulley 36, around the upper pulley 42 carried by one of the legs of the 115 shears 16 and thence around one of the pulleys of the triple pulley 39, and then back toward the forward end of the gate, and secured to the bolt 25 carried by the post 14 arranged at the front end of the 120 gate. It can be seen that when a pull is exerted on the rope 51, that a rearward pull will be exerted on the gate, which will move the gate to its open position.

From the foregoing description, it can be 125 seen that a novel gate has been provided, which can be opened or closed at three different points in a convenient and expeditious manner, and which can be easily raised or lowered without undue difficulty to permit 130

the same to ride over obstructions in the path thereof, such as stones, snow or the like.

Changes in details may be made without departing from the spirit or scope of this invention; but,

I claim:

1. In a device for opening and closing gates at points remote from the gate, a sliding gate, means for supporting the gate, supporting standards arranged on each side of the gate laterally thereof, and a supporting standard arranged rearwardly of the gate, a pair of pulleys carried by each one of the standards, an intermediate supporting post disposed between the supporting standards arranged laterally of the gate having a triple block secured thereto, and opening and closing cables carried by each of the supporting standards and trained over the pulleys carried by said standards, certain of said pulleys being extended directly to the ends of the gates, while others have their intermediate portions trained around the triple block carried by the intermediate support.

2. In a device for opening and closing a gate at points remote from the gate, a sliding gate, upstanding posts carried by the opposite ends of the gate having vertically aligned guide ways formed therein, a supporting rod, means for holding the supporting rod in a raised position, wheels arranged in the slotted guide portions of the posts engaging the upper surface of the supporting rod, a brace connecting the upper end of the posts together, and fastening bolts secured to the posts adjacent to their upper ends and in said guide ways, and means permitting adjustment of the supporting rollers and the bolts and the brake rod in relation to the gate, supporting standards arranged on each side of the gate laterally thereof, a supporting standard arranged rearwardly of the gate, pairs of guide pulleys carried by the

supporting standards, an intermediate supporting post arranged between the supporting standards positioned laterally of the gate, a triple block carried by the intermediate supporting post, guide pulleys carried by the supporting means for the supporting rod, and a pair of flexible pulley ropes carried by the pulleys of each of the supporting standards, certain of the pulling ropes being extended directly to the ends of the supporting posts carried by the ends of the gate, and the other of the pulling ropes having their intermediate portion trained around the triple block and then extended to the bolts carried by the posts secured to the gate.

3. In a supporting structure for gates, a sliding gate, shears arranged at the opposite ends of the gate, each shear including a pair of pivotally connected legs, a supporting member carried by the shears and arranged between the legs thereof, a post carried by each end of the gate, guide wheels carried by the posts arranged to engage the supporting member carried by the shears, the supporting member being adapted to be raised and lowered by movement of the legs of the shears toward and away from each other.

4. A supporting structure for gates, a sliding gate, an upstanding post carried by the gate at each end thereof, vertically aligned guide ways carried by the gate, guide wheels adjustably mounted in said guide ways, shears arranged at the opposite ends of the gate each shear including a pair of legs, means pivotally connecting the pairs of legs together adjacent to their opposite ends, a supporting member arranged over the shears engaging the supporting wheels, the legs of the shears being adapted to be moved toward and away from each other in order to move the gate toward or away from the ground.

LORENZO JOHNSON.
